UNITED STATES PATENT OFFICE.

GAYLEN RUPERT DUNCAN, OF THREE RIVERS, CANADA, ASSIGNOR OF
THREE-FOURTHS TO DRUMMOND, McCALL & CO., A FIRM.

MACHINE FOR CONCENTRATING MINERAL ORES.

SPECIFICATION forming part of Letters Patent No. 784,146, dated March 7, 1905.

Application filed May 16, 1903. Serial No. 157,349.

To all whom it may concern:

Be it known that I, GAYLEN RUPERT DUNCAN, master of science, electrical and mining engineer, a subject of His Majesty the King 5 of Great Britain and Ireland, residing at Three Rivers, in the Province of Quebec, Dominion of Canada, have invented new and useful Improvements in Machines for Concentrating Mineral Ores, of which the following is a specification.

My invention relates to machines used for concentrating mineral ores, and has for its object the more perfect and complete separation of the valuable ore from the refuse and to 15 greatly increase the output of the machine by allowing a heavier load of pulp.

My invention is applicable more especially to vibrating concentrating-tables.

In the operation of concentrating where 20 the specific gravities of the valuable ore and the refuse material are closely approximate there is always great difficulty in obtaining a complete separation of the solid material in the pulp on account of the solid matter rapidly 25 settling on the bed of the concentrating-table. The wash-water which flows in a continuous stream across the solid material as it gradually travels forward, owing to the vibration of the table, does not sufficiently disturb this matter 30 which has settled on the surface of the table. My invention is designed to keep this solid matter disturbed, and thus allow the wash-water to more effectually carry off the lighter portion.

It consists in an apparatus to furnish a 35 shower of water in drops arranged to be adjustable as to its height, by which means the intensity of the action may be increased or diminished.

Reference will be made to the annexed drawings, in which—

Figure 1 shows a plan view of a rectangular concentrating-table with my apparatus in position; Fig. 2, a side elevation of the same 45 apparatus; Fig. 3, a plan view of a diagonal concentrating-table.

My apparatus consists of a rhomboidal pan, in the bottom of which are pierced a large number of small holes. The pan is hung upon

adjustable supports attached to the stationary 50 frame of the machine or to the floor or foundation on which table sits. A suitable supply of water feeds the pan. The position and shape of the pan will vary somewhat according to the design of the machine; but it is to be so 55 arranged as to act upon the pulp after it has left the feed-box and is proceeding toward the concentrates-box and the tailings-box. The number of holes to be pierced in the bottom of the pan will depend upon the amount 60 of agitation in the solid material required to cause a complete separation. Thus where the refuse is much lighter than the concentrates a narrower pan with fewer apertures will answer. The height to which the pan-supports 65 are adjusted will regulate the impact force of the drops, and will also depend upon the difference in specific gravity of the refuse and the concentrates. A suitable tap to the water-feed will regulate the amount of water supplied to the pan.

In operation it is found that the solid matter in the pulp coming under the influence of the drops of water is disturbed and the lighter portions are more readily acted upon by the 75 wash-water. The table 1 is given a reciprocating or gyrating vibration by the operating mechanism 10. The pulp-feed box 2 and the wash-water box 3 extend along the side which is raised, so that the flow of the pulp and 80 wash-water is in the direction of the arrows 21 31. The tailings-box 5 is situated at the opposite side of the table, while the concentrates are collected at the end of the table in the box 4. The heavier portion of the pulp 85 settles on the surface of the table and is carried toward the far end of the table by the vibration approximately in the direction of the arrow 22. The wash-water flows across this advancing bed of material. The rhomboidal-shaped pan 6, with a perforated bottom 61, is suspended over this area on adjustable supports 62. In Fig. 2 the uprights 63 have adjustment-screws 64 to raise or lower the cross-bars 62. A shower of drops falls on the 90 stream of wash-water and disturbs the bed of material beneath. The effect of this is to enable the wash-water to carry off the lighter 95

- portion, while the amount of wash-water is thus also increased. By means of this attachment to a concentrating-table not only is the efficiency of separation greatly improved, but the quantity of pulp that can be treated by a table is largely increased, a difference of over twenty-five per cent. in the output being gained in practice by the use of the attachment.
- 10 Having now described my invention, what I claim, and desire to secure by Letters Patent, is—
1. In a machine of the class described the combination of a pulp-feed, a wash-water supply and a dropping-pan adapted to supply a shower of drops of water upon the stream of wash-water and the material which has settled on the surface of the machine beneath the stream of wash-water.
  - 15 2. In a concentrating-table, the combination of a pulp-feed, a wash-water supply and a dropping-pan situated upon the area traversed by the concentrates in passing to the ore-box and across which the wash-water flows to the tailings-box and adapted to disturb the wash-water and the settled material beneath.
  - 20 3. The combination with a concentrating-table, of an adjustable dropping-pan adapted to furnish water in the form of drops upon the surface of the table between the pulp-feed
  - 25
  - 30

and wash-water supply and the tailings and concentrates boxes.

4. In a concentrating-table in which the concentrates pass over the far end of the table for the pulp-feed and the wash-water 35 passes across the table, a dropping-pan and water-supply adapted to disturb by means of a shower of drops the stream of wash-water and the settled material beneath.

5. In an ore-separator the combination of 40 a vibrating table and a dropping-pan adapted to disturb by means of a shower of drops the whole area in which the concentrates pass across the flow of the wash-water as described.

6. In an ore-separator a dropping-pan 45 adapted to disturb by means of a shower of drops the concentrates in the area across the path of which the wash-water flows as described.

7. In an ore-concentrator, a dropping-pan 50 adapted to disturb by means of a shower of drops the wash-water flowing across the path of the concentrates as described.

In testimony whereof I have signed my name to this specification in the presence of two sub- 55 scribing witnesses.

GAYLEN RUPERT DUNCAN.
